UNITED STATES PATENT OFFICE.

VINCENT BENDIX, OF CHICAGO, ILLINOIS.

ENGINE-STARTER.

1,327,302.

Specification of Letters Patent.

Patented Jan. 6, 1920.

Application filed March 21, 1919. Serial No. 284,052.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to a starter for an engine such as an internal combustion engine and the object thereof is to produce an automatic drive or transmission therefor of novel and efficient construction and mode of operation.

My new construction of drive belongs to that general type as exemplified by patents heretofore issued to me such as Patent No. 1,125,935 dated January 26, 1915 and No. 1,274,370 dated August 6, 1918, according to which a driving member, whether the pinion itself which engages the engine member such as the fly wheel or a separate member which controls such a pinion, is mounted on a rotatable shaft such as a screw shaft and automatically causes engagement of the drive with and its disengagement from the engine member after the engine has started on its own power.

One of the main objects of my invention is to relieve the rotatable member or screw shaft of the driving load and to place such load upon a separate shaft which may be directly or indirectly driven by the starting motor or other sources of power, and on which the driving pinion may be rather closely fitted instead of the necessarily loose fit if such pinion were mounted upon a screw shaft. Moreover my construction enables the shifting mechanism to be made comparatively small and light and the actual driving parts to be made of any size according to the particular requirements as to load or location.

In the drawings Figure 1 is a sectional elevation of a starter embodying my new construction of drive; Fig. 2 an elevation of the driving gear; Fig. 3 an elevation of the driving pinion; Fig. 4 a sectional elevation similar to Fig. 1 but showing the parts in driving position; and Fig. 5 a section on the line 5-5 of Fig. 4.

Before describing the particular embodiment of my invention as herein shown it will be understood that the parts may partake of considerable change or variation in the broader aspect of my invention, and also that the power of the motor may be applied

indirectly instead of directly as shown, that is, through an extended armature shaft.

As shown the prime mover is a starting motor indicated at A and having an extended armature shaft 1 on which is more or less accurately fitted the driving member which is here in the form of a pinion 2. This pinion is adapted to mesh with the teeth 3^a of a fly wheel 3. This pinion is provided at its outer or rearward end with a separate or integral gear 4 which is of the flanged or shroud type by reason of the provision of the extending marginal flanges 4^a. The detailed construction in respect to this gear is immaterial but in the present instance these flanges are separate from the pinion body and are formed by annuli secured thereto in suitable manner as by means of the stud bolts 5.

The pinion 2 is formed at its inner or front end with inclined clutch jaws 6 which are adapted to cooperate with complementary clutch jaws 7 formed at the front edge of the hub 8^a of a driving gear 8. This gear is secured in suitable manner to the driving shaft 1 as by means of the key 9.

In my new construction the rotatable shaft 10 for the shifting mechanism, that is the screw shaft is a countershaft with respect to the driving shaft 1 and the same is mounted or journaled in parallel relationship therewith in any suitable manner as by means of the bearings 11 and 12 in the casting or bracket 13, for supporting the outer ends of such shaft. To the inner end of this shaft there is secured in suitable manner as by the pin 14 a gear 15 in constant mesh with the gear 8, whereby the rotation of the motor and driving shaft 1 is always communicated to the shaft 10. This latter shaft has a screw threaded portion 10^a upon which is screw threaded a shifting or screw member 16, here in the form of a gear having the same diameter and number of teeth as the gear 15. The gear 16 being thus threaded upon the screw shaft is capable of an automatic longitudinal movement along such shaft and also a rotary movement therewith when arrested in its longitudinal movement in the manner hereinafter explained. This gear 16 is in constant mesh with the gear 4 of the pinion 2 and by reason of the shroud character of such latter gear, these two gears partake of each other's rotary and longitudinal movements.

It will be understood that the gear 4, like

the gear 16 with respect to the gear 15, is of the same diameter and has the same number of teeth as the gear 8. All of these four gears may be of the same diameter and of 5 the same number of teeth but this is not essential so long as there is the same gear ratio between the gears 4 and 16 as between the gears 8 and 15.

Describing a cycle of operation and beginning with the parts in their position as 10 illustrated in Fig. 1, the rotation of the motor is transmitted through the gears 8 and 15 to the countershaft or screw shaft 10. As a result the gear 16 is automatically 15 moved longitudinally to the left, thereby carrying or sliding the pinion 2 inwardly along the driving shaft 1. This shifting of the pinion 2 brings the same into mesh with the fly wheel 3 and also brings the two 20 clutch jaws 6 and 7 into engagement. Whereupon the pinion is rotated directly and positively by the gear 8 at this time, the parts now occupying the relative position shown in Fig. 4. The gears 15 and 16 25 and also the shaft 10 will be rotated but idly so inasmuch as all of the driving load is taken and sustained by the driving shaft 1.

It will be understood that in this construction the pinion 2 is in full mesh and 30 in clutch engagement with the gear 8 before the gear 16 reaches the end of the screw threads 10^a, with the result that when the longitudinal movement of the parts to the left is stopped by said engagement the gear 16 will no longer advance in said direction but will partake of the rotary movement of its shaft.

When the engine has started on its own power the increased rate of rotation of the 40 fly wheel causes an excess of rotation as compared with the speed of rotation imparted by the starting motor with the result that this excess rotation communicated by the pinion 2 and its gear 4 to the gear 45 16 will cause the automatic movement of said parts to the right and the consequent demeshing of the pinion 2 from the fly wheel.

If desired suitable means may be employed to coöperate with the gear 16 in 50 order to hold the same in retracted or disengaged position as shown in Fig. 1. In the drawings I have shown such a construction the same comprising a shell 17 having an internal flange 17^a and secured to the hub 16^a of the gear by screws 18. This flanged shell is adapted to coöperate with a catch carried at the outer or right hand end of the screw shaft. This catch 55 comprises a pin slidingly mounted transversely through this shaft and normally held projected in one direction by the coil spring 20, such sliding movement being limited by the collar 21 on such pin. This 60 pin is provided with 2 lateral parallel

brackets 22 and 23 on which is mounted a latch 24 normally yieldingly pressed upwardly above the bracket 23 by the coil spring 25. This latch has an inclined top edge so that the same will be depressed 70 when contacted by the flange 17^a but to catch therebehind after such flange has cleared the latch. Inasmuch as the weight on the bracket side of the pin or rod 19 exceeds its weight on the other side, such 75 weighted portion will be thrown outwardly by the centrifugal force due to rotation of the screw shaft so that the latch will be projected outwardly as shown in Fig. 4 in position to catch the shell 17. When the screw shaft 80 and other parts come to rest the catch mechanism will be restored to its central position and will disengage itself from the flange 17^a, thereby permitting the gear 16 to move 85 freely on the next operation. The latch 24, is in engagement with the shell 17 at the time when the parts are still rotating and when it is desired to keep the gear 16 in retracted position and prevent it from advancing longitudinally again which might 90 have the effect of clashing the pinion 2 with the fly wheel. Obviously, this catch device could be mounted on the driving shaft in position to coöperate with the pinion 2.

I claim:

1. In an engine starter, a drive comprising a rotatable driving shaft, a driving member mounted thereon for longitudinal movement thereof for engagement with a part of the engine to be started, and for 100 rotary movement therewith, and means mounted extraneous of such shaft and out of the line of load for automatically moving the driving member longitudinally.

2. In an engine starter, a drive comprising a rotatable driving shaft, a driving member mounted thereon for longitudinal movement thereof for engagement with a part of the engine to be started, and for rotary movement therewith, and screw 110 shift means mounted extraneous of such shaft and out of the line of load for so moving the driving member longitudinally.

3. In an engine starter, a drive comprising a rotatable driving shaft, a driving member mounted thereon for longitudinal movement thereof for engagement with a part of the engine to be started, and for rotary movement therewith and also for rotary movement thereof, and means mounted 120 extraneous of such shaft and out of the line of load for so moving the driving member longitudinally.

4. In an engine starter, a drive comprising a rotatable driving shaft, a driving member mounted thereon for longitudinal movement thereof for engagement with a part of the engine to be started, and also for rotary movement therewith, and means mounted extraneous of such shaft and out 130

of the line of load for so moving its driving member longitudinally, such means being actuated by the shaft in its rotation.

5. In an engine starter, a drive comprising a rotatable member, a driving member mounted to slide longitudinally thereon for engagement with a part of the engine to be started and also with such rotatable member, and means extraneous of the rotatable member and out of the line of load for automatically so moving the driving member.

6. In an engine starter, a drive comprising a rotatable driving shaft, a driving member mounted thereon for longitudinal movement thereof for engagement with a part of the engine to be started, and also for rotary movement therewith, a countershaft driven by said driving shaft and out of the line of load, and means mounted on 20 the countershaft for automatically so moving the driving member longitudinally upon rotary movement of the countershaft.

7. In an engine starter, a drive comprising a rotatable driving shaft, a driving member mounted thereon for longitudinal movement thereof for engagement with a part of the engine to be started, and also for rotary movement therewith, a countershaft driven by said rotatable shaft, and 30 a control member mounted thereon for longitudinal movement thereof and rotary movement therewith and coöperating with the driving member to shift it longitudinally.

8. In an engine starter, a drive comprising a rotatable driving shaft, a driving member mounted thereon for longitudinal movement thereof for engagement with a part of the engine to be started, and also 40 for rotary movement therewith, a countershaft driven by said rotatable shaft and having screw threads, a screw member threaded thereon for automatic longitudinal movement thereof and rotary movement therewith and coöperating with the driving member to shift it longitudinally.

9. In an engine starter, a drive comprising a rotatable driving shaft, a driving member mounted on the shaft and adapted 50 to be shifted thereon, and means including gearing for automatically controlling the shifting movements of the driving member, such means being out of the line of load.

10. In an engine starter, a drive comprising a rotatable driving shaft, a driving member mounted on the shaft and adapted to be shifted thereon, and means including a second shaft and gearing between the latter shaft and the driving member for automatically controlling the shifting movements of the driving member, such means being out of the line of load.

11. In an engine starter, a drive comprising a rotatable driving shaft, a driving member mounted thereon for longitudinal

movement thereof for engagement with a part of the engine to be started, and also for rotary movement therewith, shifting means mounted extraneous of the driving shaft and coöperating with the driving member, and gearing between the driving shaft and the shifting means and out of the line of load.

12. In an engine starter, a drive comprising a rotatable driving shaft, a driving member mounted thereon for longitudinal movement thereof for engagement with a part of the engine to be started, and also for rotary movement therewith, shifting means mounted extraneous of the driving shaft and coöperating with the driving member, and two sets of gearing, one between the driving shaft and the shifting means, and the other between the shifting means and the driving member said gearing being out of the line of load.

13. In an engine starter, a drive comprising a rotatable driving shaft, a driving member mounted thereon for longitudinal movement thereof for engagement with a part of the engine to be started, and also for rotary movement therewith, shifting means mounted extraneous of the driving shaft and coöperating with the driving member, and two sets of gearing, one between the driving shaft and the shifting means, and the other between the shifting means and the driving member, said two sets of gearing having the same gear ratio.

14. In an engine starter, a drive comprising a rotatable driving shaft, a driving member mounted thereon for longitudinal movement thereof for engagement with a part of the engine to be started, and also for rotary movement therewith, shifting means out of the line of load and mounted extraneous of the driving shaft and coöperating with the driving member including a second shaft, and two sets of gearing, one between the two shafts and the other between the second shaft and the driving member.

15. In an engine starter, a drive comprising a rotatable driving shaft, a driving member mounted thereon for longitudinal movement thereof for engagement with a part of the engine to be started, and also for rotary movement therewith, shifting means mounted extraneous of the driving shaft and coöperating with the driving member including a second shaft, and two sets of gearing, one between the two shafts and the other between the second shaft and the driving member, the two sets of gearing having the same gear ratio.

16. In an engine starter, a drive comprising a rotatable driving shaft, a driving member mounted thereon for longitudinal movement thereof for engagement with a part of the engine to be started, and also

- for a rotary movement therewith, shifting means mounted extraneous of the driving shaft and coöperating with the driving member, and gearing between the driving 5 shaft and the shifting means, including a second shaft, gearing between the two shafts for driving the latter, a control member mounted on the second shaft for longitudinal movement thereon, and gearing between 10 the control member and the driving member, said two gearings having the same gear ratio.
17. In an engine starter, a drive comprising a rotatable driving shaft, a driving member mounted thereon for longitudinal movement thereof for engagement with a part of the engine to be started, and also for rotary movement therewith, a countershaft, driving gearing between the two shafts, a control 15 member mounted on the countershaft for longitudinal movement thereof and rotary movement therewith and being geared to the driving member with the same gear ratio as said driving gearing, said control 20 member being arranged to shift the driving member longitudinally.
18. In an engine starter, a drive comprising a rotatable driving shaft, a driving member mounted thereon for longitudinal movement thereof for engagement with a part of the engine to be started, and also for rotary movement therewith, a countershaft driven 25 by said rotatable shaft and having screw threads, and a gear threaded thereon for automatic longitudinal movement thereof and rotary movement therewith, said driving member having gear teeth with which such gear meshes and also being engaged by the gear whereby the latter shifts it longitudinally on the driving shaft.
19. In an engine starter, a drive comprising a rotatable driving shaft, a driving member mounted to slide longitudinally thereon for engagement with a part of the engine to be started, said shaft and member having coöperating clutch elements engaged when such member is in engagement with the engine part, and means mounted 45 extraneous of the shaft for automatically moving the driving member.
20. In an engine starter, a drive comprising a rotatable driving shaft, a driving member mounted thereon for longitudinal movement thereof for engagement with a part of the engine to be started, and also for 55 rotary movement therewith, and means movable on an axis parallel to the axis of the shaft and operatively connected with the driving member to so shift it longitudinally, said means being out of the line of the load.
21. In an engine starter, a drive comprising a rotatable driving shaft, a driving member mounted thereon for longitudinal movement thereof for engagement with a 65 part of the engine to be started, and also for rotary movement therewith, a countershaft driven by said rotatable shaft, a control member mounted thereon for longitudinal movement thereof and rotary movement therewith and coöperating with the driving member to shift it longitudinally, and means for holding the driving member in disengaged position.
22. In an engine starter, a drive comprising a rotatable driving shaft, a driving member mounted thereon for longitudinal movement thereof for engagement with a part of the engine to be started, and also for rotary movement therewith, a countershaft driven by said rotatable shaft, a control member mounted thereon for longitudinal movement thereof and rotary movement therewith and coöperating with the driving member to shift it longitudinally, and means coöperating with the control member for holding it in disengaged position.
23. In an engine starter, a drive comprising a rotatable driving shaft, a driving member mounted thereon for longitudinal movement thereof for engagement with a part of the engine to be started, and also for rotary movement therewith, a countershaft driven by said rotatable shaft, a control member mounted thereon for longitudinal movement thereof and rotary movement therewith and coöperating with the driving member to shift it longitudinally, and speed controlled means coöperating with the control member for holding it in disengaged position.
24. In an engine starter, a drive comprising a rotatable driving shaft, a driving member mounted thereon for longitudinal movement thereof for engagement with a part of the engine to be started, and also for rotary movement therewith, a countershaft driven by said rotatable shaft, a control member mounted thereon and coöperating with the driving member to shift it longitudinally and a speed controlled catch device mounted on the countershaft and arranged to engage and hold the control member in disengaged position.
25. In an engine starter, a drive comprising a rotatable driving shaft, a driving member mounted thereon for longitudinal movement thereof for engagement with a part of the engine to be started, and also for rotary movement therewith, a countershaft driven by said rotatable shaft, a control member mounted thereon and coöperating with the driving member to shift it longitudinally, a flanged member on the said control member, and a speed controlled catch device mounted on the countershaft, including a latch adapted to engage and hold the flanged member when the countershaft is rotating.
